UNITED STATES PATENT OFFICE.

GUY M. BEAN, OF LOS ANGELES, CALIFORNIA, ASSIGNOR TO AMERICAN ARCH COMPANY, A CORPORATION OF DELAWARE.

OIL-BURNING-LOCOMOTIVE FIREBOX.

1,369,077.

Specification of Letters Patent. Patented Feb. 22, 1921.

Application filed September 11, 1919. Serial No. 323,115.

To all whom it may concern:

Be it known that I, GUY M. BEAN, a citizen of the United States, residing at Los Angeles, in the county of Los Angeles and State of California, have invented certain new and useful Improvements in Oil-Burning-Locomotive Fireboxes, of which the following is a specification.

This invention relates to improvements in oil burning locomotive fire-boxes, and its object and advantages will be best understood from a brief statement of the development of this art.

Apparently the first locomotive equipped with oil burning apparatus in this country employed what is known as the front end burner, that is, the burner was located in the front of the box. This arrangement was relatively unsatisfactory, the efficiency, particularly with respect to fuel consumption being low and the arrangement being unsatisfactory in other respects. The result of experiments with this locomotive eventually brought about the almost complete use of the back end burner, combined with a low short arch over the front of the flame channel, and this arrangement was relatively successful on small powered locomotives, and is still to some extent employed in such small power locomotives.

However, on the advent of larger powered locomotives, with their wide fire-boxes and other changes and departures from the old practice, it was found that the back end burner could not be successfully employed for the following reasons: In the first place, the arch over the flame channel was hard to maintain due to the high heat generated in the small combustion space, and to spalling incident to the admission of air under the arch in the zone of intense heat. In the next place, the increase in size and power of the locomotives necessarily involve the utilization of correspondingly increased amounts of fuel, which in turn necessitated an increase in the rate of firing, the result being the setting up of a blow-torch action in the relatively small combustion chamber which concentrated the heat on the door sheets and burned them out. In addition, particularly when the arch was not in the best of condition, this concentration also localized on the side sheets and burned them out.

The foregoing difficulties again brought

about the use of the front end burner arrangement with an open furnace on the large locomotives.

One of the important objects of my invention resides in the provision of an improved fire-box whereby I am enabled to use a back end burner without encountering the foregoing difficulties and whereby the efficiency of the locomotive is greatly increased, particularly with reference to economy in fuel consumption.

Another object of my invention resides in the provision of an improved fire-box by means of which the complicated firing valve operating conditions, ordinarily encountered in oil burning apparatus for locomotives, are eliminated.

Still another object of the invention resides in the provision of an improved fire-box whereby I am enabled to obtain a longer flame travel; whereby a reverberatory action on the flame, particularly in the earlier stages of combustion, is obtained; and whereby the air that might otherwise reach the flues at times of low rates of firing is heated.

My invention also contemplates the provision of a fire-box by the use of which the piping is simplified, and also the provision of an improved means for sanding the flues.

The foregoing, together with such other objects as may hereinafter appear, I obtain by means of a construction which I have illustrated in preferred form in the accompanying drawings, wherein:

Figure 1 is a longitudinal section through a locomotive fire-box embodying my improvements; Fig. 2 is a section taken on the line 2—2 of Fig. 1; Fig. 3 is a section taken on the line 3—3 of Fig. 1; Fig. 4 is a longitudinal section through a modification of my invention; and Fig. 5 is a longitudinal section through a locomotive fire-box illustrating the application of my invention in connection with a Gaines wall.

Referring now to Figs. 1 to 3 inclusive, it will be seen that the fire-box structure comprises the usual inside and outside throat sheets 7 and 8; the inside and outside side sheets 9 and 10; the inside and outside back sheets 11 and 12; a crown sheet 13, the cover or roof sheet 14; the flue sheet 15; and the flues 16. Circulation tubes 17 extend rearwardly and upwardly

connecting the front water leg to the rear water leg. Those features by which I am enabled to use the foregoing structure to obtain the desired results will now be described.

The bottom of the fire-box is closed by a long and relatively narrow pan 18, the side walls 19 and 20, the end walls 26 and 27, and the bottom wall 21 whereof are lined 10 with refractory material such as brick; and by the front, rear, and side shelves, respectively numbered 22, 23, 24 and 25. It will be seen from the foregoing that the pan, considered as a whole, occupies a middle 15 position in the bottom of the fire-box, with the shelves located approximately at the level of the mud ring, the pan projecting downwardly.

Located immediately in advance of the 20 front wall of the pan is a cross bearer 28 adapted to form the support for a transverse flash wall 29. Extending rearwardly from the flash wall, and supported on the circulation tubes 17 is a refractory arch 30, 25 preferably built up from a plurality of arch bricks. Extending forwardly from the rear wall 27 of the pan is what I term a primary arch 31, preferably composed of arch brick of crown shape. The primary arch is relatively 30 short in length, and the length of the arch 30 is such that the end thereof comes approximately above the end of the primary arch.

An opening 32 is provided in the rear 35 wall 27 of the pan for the purpose of introducing air, and located in such opening is the burner 33. Near the front, the bottom wall 21 of the pan is also provided with an air inlet opening 34 covered by a boot 35 40 through which air is admitted under control by means of a damper 36.

By the foregoing arrangement it will be seen that the fuel is introduced by the burner into what may be termed a primary 45 mixing chamber under the primary arch 31 where it is mixed with the air, the flow of which is induced through the opening 32. This primary chamber I have designated by the reference letter A. Ignition also 50 takes place in the primary chamber, and the flames travel therefrom into the flame channel, indicated as a whole by reference letter B. The flame channel B may be described as a combustion chamber, of relatively 55 small size, opening, however, into a second combustion chamber C, of relatively much larger size, such latter chamber having the width of the box and a substantial depth by reason of the fact that the arch 60 30 is tube supported. By this arrangement the disadvantages incident to the high rate of firing necessary are overcome for it will be seen that the fuel travel, while very rapid in the primary chamber A, slows up in the 65 flame channel B because such channel or

chamber opens into the much larger chamber C, and is still much slower through the chamber C.

The slowing up of the fuel and flame flow eliminates the blow torch action and the 70 difficulties incident thereto which have been previously described, and at the same time more perfect combustion is obtained, first in the flame channel B, and later in the chamber C. In the chamber B the fuel is 75 more effectively broken up into gases which are thoroughly mixed and baffled in the chamber C beneath the arch 30, where their travel is relatively still slower and their more complete combustion assured. The 80 gases and flame passing over the end of the arch 30 must still traverse the length of the final combustion chamber D, before reaching the flues, and since this chamber is of larger capacity than the chamber C, 85 it will be seen that all of the gases are consumed in the fire-box. The flame travel is thus a long and tortuous one, with decreasing speed. It will also be noted that the arrangement of the refractory chambers 90 is such that the flame, particularly in the earlier stages of combustion, is subjected to a reverberatory action, tending to promote more perfect combustion.

In addition I have found that this arrangement 95 enables me to dispense with a more or less involved firing valve mechanism heretofore found necessary in such forms of equipment and I am, therefore, enabled to eliminate many of the complications incident thereto. Furthermore it will be noted that the piping is greatly simplified.

Since the total air inlet opening is preferred 105 based upon the maximum rate of firing, excess quantities of air may be drawn into the fire-box at low rates of firing, but such air will be heated, before reaching the flues, in its passage through the refractory chambers.

In the modification shown in Fig. 4, the general arrangement is the same as that described, but in this instance the bottom of the pan 18 is arranged in substantially the same plane as the mud ring of the fire-box, 110 the side and back shelves coming well above the level of the ring.

In the modification shown in Fig. 5, I have illustrated the application of the general arrangement shown in Fig. 1 to a fire-box of the Gaines type, for which purpose the flash wall 29, is preferably located immediately behind the Gaines wall 37 and the air inlet openings through the latter, indicated at 38 are carried through the flash 115 wall. In this form therefore, air is admitted at three points.

Referring now to the means for sanding the flues, the ordinary method pursued is to provide a hole in the fire door allowing the 120 125 130

draft to draw the sand through the fire-box to the flues. I have found this to be unsatisfactory for the reason that a large proportion of the sand cannot be carried over 5 the arch and to overcome this difficulty I provide a thimble 40 beaded into the inside and outside back sheets 11 and 12 located just beneath the point of juncture with the crown sheet. This arrangement affords a 10 very effective means for sanding the flues.

I claim:

1. In an oil burning locomotive fire-box, the combination of a mixing chamber in the bottom of the box and toward the rear 15 thereof, a narrow combustion chamber forward of the mixing chamber and opening therefrom, and a wide combustion chamber located above and in open communication with the narrow combustion chamber and 20 having its upper side formed of refractory arch bricks, and circulation tubes for supporting the arch.

2. In an oil burning locomotive fire-box, the combination of means for closing the 25 bottom of the fire-box inclusive of a mixing chamber and a narrow combustion chamber forward of the mixing chamber and communicating therewith, and a wide combustion chamber located above and in open communication 30 with the narrow combustion chamber, said wide combustion chamber being formed in part by a transverse flash wall and by an arch composed of refractory arch brick, and circulation tubes for supporting the arch.

3. In an oil burning locomotive fire-box, the combination of a plurality of inclined 35 arch tubes located a substantial distance above the bottom of the fire-box, means for closing the bottom of the fire-box inclusive of a primary combustion chamber and a narrow combustion chamber communicating therewith, said chamber projecting downwardly, and a wide combustion chamber 40 located above the narrow combustion chamber and in open communication therewith, said wide combustion chamber having one end wall thereof composed of a refractory flash wall and having its top formed of a 45 refractory arch consisting of a plurality of arch bricks supported from said tubes.

4. In an oil burning locomotive fire-box, the combination of means for closing the bottom of the fire-box, inclusive of a narrow 55 trough extending longitudinally of the bottom of the box, a primary arch over one end of said trough adapted to form a mixing chamber, means whereby air is admitted to said mixing chamber, a burner for introducing oil into said mixing chamber, and a 60

combustion chamber of relatively large capacity located above and in open communication with the uncovered portion of the trough, the products of combustion passing over said large combustion chamber to the 65 flues.

5. In an oil burning locomotive fire box, the combination of a narrow combustion chamber in the lower portion thereof, a wide combustion chamber located above and in 70 open communication with the narrow combustion chamber and having its upper side formed of refractory arch bricks, and circulation tubes for supporting the bricks.

6. In an oil burning locomotive fire box, 75 the combination of an inclined arch tube located above the bottom of the fire box, a narrow combustion chamber for closing the bottom of the fire box, a burner for introducing oil into the rear of said narrow combustion chamber, and a wide combustion chamber located above the narrow combustion chamber and in open communication therewith, said wide combustion chamber 80 having its top formed of a refractory baffle 85 supported from the circulation tubes.

7. In an oil burning locomotive fire box, the combination of means for closing the bottom thereof, inclusive of a trough extending longitudinally of the bottom of the 90 box, a primary arch over one end of said trough adapted to form a mixing chamber, a burner for introducing oil into said mixing chamber, a combustion chamber of relatively 95 large capacity located above and in open communication with the uncovered portion of the trough, circulation tubes extending above the combustion chamber, and a refractory baffle forming the top of the combustion chamber and supported on said 100 tubes, the products of combustion passing over said large combustion chamber to the flues.

8. In an oil burning locomotive fire box, the combination of means for closing the 105 bottom thereof inclusive of a longitudinally extending trough, a primary arch extending forwardly over the rear portion of said trough, adapted to form a mixing chamber, a burner for introducing oil into said mixing chamber, circulation tubes above the trough, a flash wall at the forward end of the trough and a refractory arch supported on said tubes extending to the rear of said flash wall, said arch terminating at a point 110 approximately above the end of the primary arch.

In testimony whereof I have hereunto signed my name.

GUY M. BEAN.
